ABSTRACT: A planar monolithic circuit is made with a plurality of transistors in a single isolated region in a common emitter circuit configuration. An N-type epitaxial layer constitutes the emitter region into which the base regions of a P-type material are subsequently diffused, and an N-type collector is then diffused into the base regions forming NPN transistors. The N-type epitaxial region can simultaneously be the common collector region for some of the transistors and the common emitter region for other ones of the transistor in an operative circuit arrangement. Three transistors in a single isolated region can be formed in the shape of an "L" so that when two of these are interlinked, a rectangle is formed.

INTEGRATED CIRCUIT HAVING MONOLITHIC INVERSELY OPERATED TRANSISTORS

BACKGROUND OF THE INVENTION

The invention relates to a monolithic electric circuit containing a pair of transistors connected on the emitter side, preferably a storage cell with an internal bistable directly cross-coupled transistor multivibrator and an external differential amplifier controlled by the different collector potentials of the multivibrator.

Such circuits in the form of differential amplifiers, current switches or transistor flip flops are frequently used in electrical engineering. Planar technology is utilized for transistors in monolithic design. Irrespective of their circuitry, transistors are generally represented by the collector being disposed in the epitaxial layer on the substrate, the base in a succeeding diffusion and the emitter in a further diffusion layer above the base. Two transistors are normally insulated from each other by a P+—diffusion interrupting the n-epitaxy (collectors). Only in instances in which there is a common collector potential or in which the two collectors are linked through an epitaxial resistance, is such an insulation not required.

P+—insulations of this kind, forming separate isolation pockets, need much space on account of the lateral migration occurring during diffusion.

SUMMARY OF THE INVENTION

It is the object of the present invention to avoid such space losses by the use of insulating layers in the case of transistors connected on the emitter side and, furthermore, to eliminate metallizations for the galvanic links. To this end the invention provides for a pair of transistors designed according to planar technology and having the same emitter potential to be inversely operated, that means that in a common isolation pocket the emitters are represented in the n-epitaxial layer and the collectors as separate diffusions within the base diffusions.

A further feature of the invention provides for two series-connected transistors, the emitter and/or collector of which is linked with the same potential, to be designed in planar technology so that one transistor is operated in the normal manner while the other one, connected on the emitter side, is inversely operated.

Difficulties in the arrangement in accordance with the invention may occur with regard to the current amplification β of the individual transistors. The value obtainable in conjunction with inversely operated transistors currently is $\beta \approx 10$. However, when using gold doping this value drops to $\beta < 1$. For many applications a current amplification of this order is adequate and a shortcoming which can be accommodated without difficulty.

An embodiment of the invention using two pairs of transistors connected on the emitter side is shown in the drawings and is hereafter described in detail.

BRIEF DESCRIPTION OF THE DRAWINGS

FIG. 1 shows an electric circuit of a proposed storage cell; FIG. 2 shows a monolithic matrix of storage cells in accordance with an electric circuit of FIG. 1;

FIG. 3 shows a cross section of a part of the monolithic storage cell of FIG. 2.

DESCRIPTION OF THE PREFERRED EMBODIMENTS

The description of the topological layout in accordance with the invention is preceded by a description of the operation of the storage cell of FIG. 1.

This storage cell, which has been previously suggested, consists of a storing element, namely a directly cross-coupled transistor flip flop 10. The latter comprises two transistors T_3 and T_4 with common emitter potential V_G . The collectors of the two transistors are linked with the operating potential V_{cc} through two collector resistors R_1 and R_2 (abt. 1 k Ω). One of the two branches carries current in each instance so that two

different pieces of information stored can be represented. Three further transistors T_1 , T_2 and T_5 are used for reading and writing. For the latter two operations the cell is addressed by a positive pulse on the X-line, causing transistor T_5 to become conductive. Reading is performed as follows: The potential of the two emitters of the transistors T_1 and T_2 is lowered upon addressing transistor T_5 ; this results in an emitter resistance not shown in FIG. 1 and common to a plurality of storage cells being linked with the emitters of the two transistors T_1 and T_2 . Through this emitter resistance the latter are connected to a negative potential voltage source, and the complete arrangement outside the flip flop 10 operates as a differential amplifier that means read current flows at B_0 or B_1 , depending upon the potentials of the flip flop collectors.

Information is written into this cell by the potential on one of the terminals B_0 or B_1 being so lowered that a base current flows over the base to the collector of the transistor T_1 (T_2) which causes the base potential on the transistor T_4 (T_3) to be decreased and the latter to be blocked.

A topological layout of a storage cell of the kind as described and in which in accordance with the invention the inverse operation of several transistors is utilized is shown in a matrix in FIG. 2 within the dotted line 11 and in FIG. 3. The transistors T_3 and T_4 , forming the multivibrator, are inversely represented, that means the two collectors C_3 and C_4 in the base diffusions B_3 and B_4 are shown within a common emitter-n-epitaxial layer. The two collector resistances in the form of bulk resistances R_1 and R_2 are disposed in a separate isolation pocket. In a third isolation pocket there are arranged the remaining three transistors T_1 , T_2 , T_5 , T_1 and T_2 of which are inversely represented so that they have one common emitter diffusion (n-epitaxy) and separate base (B_1 , B_2) and/or collector diffusions (C_1 , C_2). The common emitter diffusion is utilized at the same time as a collector diffusion of the transistor T_5 operated in a normal manner and of which are shown the base B_5 and the emitter E_5 .

FIG. 3 is a sectional view of the monolithic circuit of FIG. 2. The diffusions having different conductivities are clearly discernible. On a p-substrate in n-epitaxial pockets insulated by p+—diffusions there are on the one hand the bulk resistances R_1 , R_2 and on the other the inversely operated transistor T_4 , the collector C_4 of which has a window for contact making, the inversely operated transistor T_2 with its base B_2 and the collector C_2 , both of which can be contacted through an oxide window, and the transistor T_5 operated in a normal manner with the base B_5 and the emitter E_5 and the associated oxide windows.

We claim:

1. A planar monolithic circuit having a plurality of transistors in each of two isolated regions comprising:

two isolated regions;

at least two transistors, in the first isolated region having an epitaxial layer as a common emitter region;

cross-coupling conductors between said two transistors in said first isolated region, forming a bistable circuit;

a plurality of transistors in the second isolated region forming a control and sensing circuit for said bistable circuit at least one of said plurality of transistors in said second region having a collector region the same as an emitter region of at least another one of the said plurality of transistors in said second region; and

connecting means for establishing electrical contact between said bistable circuit and said control and sensing circuit.

2. A planar monolithic circuit having a plurality of transistors in each of a plurality of isolated regions comprising:

a first one of said plurality of isolated regions having two cross-coupled transistors in a common emitter configuration, forming a multivibrator;

a second one of said plurality of isolated regions having three transistors such that said epitaxial layer is the common emitter for two of the said transistors and the collector for the third of the said transistors;

at least two conductive paths for connecting the two transistors in the first one of said plurality of isolated regions with at least two of the three transistors in said second one of said plurality of isolated regions; whereby the two transistors in said first one of said plurality of isolated regions form a multivibrator and the three transistors in said second one of said plurality of isolated regions form a differential amplifier together with an ad-

dressable gate transistor, said combination providing an operational storage cell.

3. A monolithic storage matrix in accordance with the circuit of claim 2 wherein said second one of said plurality of isolated regions is "L"-shaped and pairs of said "L"-shaped isolated regions are interlinked, forming a rectangle.
